Patented Nov. 14, 1916.

UNITED STATES PATENT OFFICE.

SAMUEL ROSENTHAL, OF NEW YORK, N. Y.

CUFF FOR TROUSERS.

1,204,820.

Specification of Letters Patent. Patented Nov. 14, 1916.

Application filed August 10, 1916. Serial No. 114,144.

To all whom it may concern:

Be it known that I, SAMUEL ROSENTHAL, a citizen of the United States of America, a resident of the city of the New York, 5 county of New York, State of New York, have invented certain new and useful Improvements in Cuffs for Trouser, of which the following is a full, clear, and exact description, reference being had to the accompanying drawing, forming a part of this specification.

My invention relates to improvements in cuffs for trousers.

Prior to this invention, the manufacturers 15 of ready made trousers have folded the lower margins of the leg members upwardly and inwardly, thus providing excess material some of which is to be used in forming the cuffs after the required length has been 20 ascertained by the retail merchant who sells directly to the user. The cuffs are usually formed very hastily by bushelmen employed by the retailers for the purpose of altering various kinds of garments. Since these 25 workmen are not specialists, the trousers cuffs are not accurately formed and they do not have the neat appearance that could be obtained by an expert operator. Furthermore, on account of the time consumed by 30 the bushelmen, it is expensive to form trousers cuffs in the ordinary manner.

Therefore, the object of my invention is to produce trousers cuffs adapted to be made in large quantities, by expert workmen in 35 the employ of garment manufacturers, and afterward shipped to the retailers with the trousers. Neat, accurate and inexpensive trousers cuffs may be made by the expert cuff-makers, and the new cuffs are so formed 40 that they may be very easily and quickly attached to the trousers, by the bushelmen.

Figure I is a perspective view of the lower portion of a trousers leg equipped with one of my cuffs. Fig. II is a view similar to Fig. I, showing the parts as they appear before the cuff is attached to the trousers. Fig. III is an enlarged vertical section, showing the cuff attached to the trousers. Fig. IV is a view showing a pair 50 of cuffs attached to the trousers.

In manufacturing the garment, the lower portion of each leg member is folded inwardly and upwardly, as shown at 1 in Fig. II, and if desired it may be stitched at 2 in the usual manner. The separate cuffs 55 A are made by the garment manufacturer and shipped with the garment to the retailer.

Each cuff member is a continuous band, 60 made of a strip of material having its upper and lower marginal portions 3 and 4 folded toward each other as shown most clearly in Fig. III. These folded marginal portions are surrounded by the intermediate portion of the strip of material of which the cuff 65 is formed. 5 designates cement securing the folded margins to the intermediate portion of the material, and serving as a stiffener for the ready made cuff.

After the desired length has been ascertained, the lower portion of each trousers leg is usually cut and folded inwardly as shown at 1' in Figs. I and III, the folded portion being secured by means of stitches 2' at its upper edge. The folded lower edge of the 70 cuff may then be easily and quickly attached to the folded lower edge of the trousers leg, by means of stitches 6 (Fig. III). The folded lower edge of the trousers leg is concealed by the lower edge of the cuff which 75 lies in a plane below the leg member.

I claim:

A pair of trousers having the lower portion of each of its leg members folded inwardly and upwardly, a pair of cuffs 85 adapted to be attached to the folded lower portions of said leg members, each of said cuffs being independent of said trousers and comprising a continuous strip of material having its upper and lower marginal portions folded toward each other, said upper and lower marginal portions being surrounded by and cemented to the inner face of the intermediate portion of said material, and stitches securing the folded lower edges 90 of the cuffs to the folded lower edges of the leg members. 95

SAMUEL ROSENTHAL.
